UNITED STATES PATENT OFFICE

2,607,637

COOLING MEANS FOR ELEVATOR BEARING SHAFTS

Stanley M. Mercier, Bexley, Ohio, assignor to The Jeffrey Manufacturing Company, a corporation of Ohio

Original application September 1, 1943, Serial No. 500,799. Divided and this application September 24, 1949, Serial No. 117,762

4 Claims. (Cl. 308—77)

1

My invention relates to a head shaft and bearing assembly for a high temperature elevator, and an object of the invention is to provide improved means for temperature conditioning (cooling) the shaft adjacent the bearing.

Other objects of the invention will appear hereinafter, the novel features and combinations being set forth in the appended claims.

In the accompanying drawings,

Fig. 1 is a side elevational view of an elevator or conveyer incorporating the features of my invention;

Fig. 2 is a rear view of the head portion of the conveyer shown in Fig. 1, the view being taken on line 2—2 thereof; and

Fig. 3 is a transverse, fragmentary sectional view showing one end of the head shaft, bearing and head sprocket and associated mechanism of the elevator or conveyer.

This application is a division of my co-pending application, Serial No. 500,799, filed September 1, 1943, now Patent No. 2,491,899, dated December 20, 1949, entitled "Elevator".

The conveyer or elevator illustrated as a whole in Fig. 1 of the drawings comprises a vertical or upwardly extending tower or main frame 20 which is generally rectangular in cross section and at each of the four corners includes a vertical or upright structural member, such as a channel 21. Each of the channels 21 in the finally assembled condition of the main frame 20 constitutes a continuous upright member which extends from the foot or bottom of the main frame 20 to the top thereof. At their bottoms, the channels 21 are provided with feet 22 preferably rigidly attached to the base members which may be, for example, mounted on a poured concrete base sufficiently sunk in the ground to provide a firm foundation. At their tops the channel members 21 are rigidly connected together by side I-beams 23 and cross channels 24, all of said structural members 21, 23 and 24 being rigidly connected together. Along the sides, each of the two front and rear channel members 21 are connected by one or more diagonal braces 25 as well as horizontal angle members 26. Spaced moment members 27 connect the front and rear pairs of channels 21.

Mounted upon the I-beams 23 at the top of the main frame 20 is a pair of spaced bearing boxes 29 which support a horizontally extending head shaft 30 of a head assembly 31 that includes a pair of head sprocket wheels 32 which support and drive a pair of endless chain elements 33 of a bucket elevator or conveyer mechanism

2

indicated diagrammatically in Fig. 1. Extending between the two chain elements 33 and carried thereby is a plurality of material receiving buckets, not shown, that are rigidly attached adjacent their sides to the inner side bars of the chains 33 by appropriate brackets.

At the foot or bottom of the tower or main frame 20 there is a foot shaft 37 which is part of a foot shaft assembly 38 which includes a pair of spaced wheels 39 that receive and carry the two endless chain elements 33 of the conveyor apparatus. Foot shaft assembly 38 is mounted for floating guided vertical movement and is carried by a box-like frame 34 with which there is associated a counter-balancing mechanism 35 for counter-balancing weight of the box-like frame and shaft assembly.

Supported by the main frame 20 and generally within the structural members thereof is a totally enclosing casing or housing 40 which includes as its three principal parts a head section 41, a foot section 42 and a plurality of intermediate sections 43. All of these sections are preferably formed at least in part of insulating material so that the enclosing housing or casing is insulated. Also the head section 41 is provided with a discharge chute or spout 44 by which the material is discharged from the conveyer.

The foot part or section 42 of the housing or casing 40 includes a feed chute 45 by which hot clay or other material to be elevated is delivered preferably directly into the buckets at the bottom of the feed run of the conveyor mechanism. The foot section or part 42 also includes structure providing gas tight dust and heat seals for the foot shaft 37 which is mounted for substantially free or floating vertical movement through a limited range so as to compensate for changes in the lengths of the chain elements 33, particularly under the influence of temperature changes.

Attention is now directed to mechanism that is included in the head section of the conveyer and shown in Figs. 1 and 2 of the drawings. Referring thereto, it will be noted that one end 45 of the head shaft 30 is provided with a drive sprocket 46 which is keyed to the shaft 30. At its other end the shaft 30 is provided with a traction wheel 47 with which a mechanically operated brake device 48 (Fig. 1) cooperates. The drive sprocket 46 is driven from an appropriate motor and speed reducer 49 through an appropriate chain and sprocket or equivalent drive 50. The motor and speed reducing mechanism 49 is mounted on a platform formed on rearwardly extending portions of the I-beams 23.

Attention is now directed particularly to Fig. 3 of the drawings which illustrates one end of the head sprocket assembly 31, one of the bearing boxes 29, and certain associated apparatus, it being understood that the structure is duplicated on the other side of the elevator.

Mounted in spaced relation on the head shaft 30 are the head or drive sprockets 32, there being one for each of the chains 33, as previously pointed out, said sprockets 32 preferably being of similar construction. Each sprocket 32 includes a plate steel center ring 98 preferably keyed and welded to the shaft 30 and forming a hub. The additional diameter of the wheel 32 is formed by a pair of concentric rings 99 and 100, the first being shrunk onto the center ring or hub 98 and the second being in turn shrunk onto the ring 99. In building up this wheel, the ring 99 is heated to a high temperature so that it can be forced or slipped onto the ring 98 and when it cools to atmospheric temperature it will be under tension. Thereafter, the edges of the rings 98 and 99 are preferably welded together by welds 101 which may be either continuous or at spaced intervals along the periphery thereof. In a similar manner the ring 100 is shrunk on the ring 99 and attached thereto by welds 102 similar to the welds 101. The ring 100 is also under tension at atmospheric temperature.

As a consequence of the above structure, the wheel 32 can expand or contract with variations in temperature without causing damage thereto and at the same time the structure is such that the parts are held together both by friction and by welded connections. Because shaft 30 is cooled, as hereinafter described, the temperature of the wheel rim, which frequently reaches 1000 degrees F., will be much higher than the shaft temperature during operation of the conveyer.

Mounted on the outer periphery of the ring 100 is a plurality of removable sprocket teeth 103 and the bottom or root of each tooth 103 is provided with an arcuate groove which receives the periphery of the ring 100, said root of tooth 103 being bifurcated so that a portion or part thereof extends on each side of the ring 100. The final attachment between each tooth 103 and the ring 100 is by virtue of a pair of pins 104 which have a pressed or tight fit with aligned holes in the ring 100 and the root parts of tooth 103, the pins 104 preferably being welded at one or two spots to the root of tooth 103 after the parts are assembled. To remove a tooth 103 the welded spot is burned off.

To protect the major portion of the two wheels 32 from the high temperature within the casting 40 and also to reduce the transfer of heat therefrom through the shaft 30 and to its supporting bearings, the principal portion of said sprocket 32, including the rings 98 and 99 and part of the ring 100 as well as the major portion of the shaft 30 within the housing 40, is embedded in a heavy drum 105 of insulating material which is preferably made up of sections which are split along a plane passing through the axis of the shaft 30, transversely of itself. The drum 105 is also made in sections, there being at least one transverse section between the two sprockets 32 and two sections, one outside each of said sprockets, these transverse sections being connected together with tie rods 106. Similar tie rods 106 or tie bolts not illustrated, may interconnect the sections of drum 105 along their plane of severance parallel to the axis of shaft 30.

As clearly illustrated in Fig. 3 of the drawings,

the end of the drum 105 is closely positioned with respect to the insulating material lining 107 of the head section 41 of casing 40. The opposite ends of head shaft 30 extend through close fitting openings in the side walls of the head section 41 and a stuffing box 108 is provided between each of said side walls and said shaft 30 which acts as a dirt and heat seal. A support for opposite ends of the shaft 30 is provided by a pair of self aligning bearings, one of which is seen at 109. Said bearing 109 is preferably babbitt or bronze lined and is only semi-cylindrical in shape and supports the bottom portion of the shaft 30, since the load on the shaft 30 is always in a downward direction. The bearing 109 is enclosed and protected by the bearing box 29 which provides a lubrication well. Oil drip rings 110 are provided on shaft 30.

It is important in elevators or conveyers of the type illustrated that the temperature of the wheel shafts be controlled or conditioned because in spite of all of the insulation provided on the shaft assemblies the shafts will become quite hot unless they are properly cooled. It is because of the cooling of the shaft 30 and the consequent large temperature differential between it and the rim of sprocket wheel 32 that the above described special construction of said sprocket wheel 32 is required. To control its temperature the shaft is provided with an axial bore 121 whereby it is formed as a hollow shaft. It will be understood that the cooling mechanism is duplicated at each end of the shaft 30. Extending into the bore 121 is a pipe 122, the outer periphery of which is spaced from the inner periphery of the bore 121. At its outer end the pipe 122 is provided with a fitting 123 which acts in the nature of a bearing. The fitting 123 is so constructed that a feed water elbow 124 connected thereto, will be effectively connected to the interior of the pipe 122 and a water discharge elbow 125 is effectively connected to a passageway formed between the exterior of the pipe 122 and the cylindrical surface provided by the bore 121. The packing between the fitting 123 which is stationary and the rotating shaft 30 is provided by packing ring 126 and associated packing gland 127 which is attached by screws to the end of the shaft 30. The fitting 123 is mounted on a stationary bracket 128 which may be connected to any desired closely associated portion of the main frame 20.

Adjacent its inner or right hand end, as viewed in Fig. 3, the pipe 122 is provided with radial holes 129 so as to provide communication between the feed and return paths for the cooling water or other temperature controlling fluid or medium. The inner end of the pipe 122 is provided with a rigidly attached plug 130 which is supported in the end of a filler and connecting cylindrical rod 131 which extends through the central portion of the shaft 30 and supports the inner ends of the pipes 122 associated with opposite ends of said shaft 30. It may be mentioned that axial movement of the pipes 122 is prevented since the fittings 123 to which said pipes in opposite ends of the shaft 30 are screw-threaded, are held by the above mentioned stationary brackets 128. Filler rod 131 is slightly smaller in diameter than the bore 121 and is pinned at its center to the shaft 30 for rotation therewith.

To provide a thorough scouring turbulent flow of water in its return path from the holes 129 to the discharge elbow 125, I provide wire helix 75 132 which is preferably rigidly attached to the

exterior surface of the pipe 122 and is closely adjacent to the cylindrical surface of the bore 121, though slightly spaced from said surface, since the shaft 30 rotates while the wire helix 132 is stationary. It is evident that cooling water introduced by way of the feed elbow 124 will flow through the fitting 123 into the pipe 122 and out of the radial openings or holes 129 and thence will return by a greatly elongated and helical path of reduced cross-sectional area to provide what is known as "turbulent flow," during which it will scour the internal surface of the adjacent portion of the shaft 30 provided by the bore 121, ultimately flowing through the fitting 123 and the discharge elbow 125. This elongated helical path together with the scouring action will insure proper cooling of the shaft 30 and through it the bearing 109 so as to prevent burning out of said bearing and undue heating of the lubricating oil for it, which is within the bearing box 29.

In the operation of the conveyor or elevator hot material, such as clay or fuller's earth, is fed to the feed chute 45 and by it directed into the buckets of the conveyor mechanism as they travel upwardly from the foot shaft assembly 38 along their working or elevating run. As the buckets travel over the head shaft 31 they discharge into the discharge chute 44 and the material flows therethrough and is discharged from the elevator at the top thereof. Provision has been made for free vertical counter-balanced movement of the foot shaft, which movement may be caused by differences in temperature within the casing or housing 40. Furthermore, the head sprocket wheels for the two strands of chain 33 have been especially constructed to take care of differences in temperature adjacent the outer rims thereof as compared with the hubs or portions thereof attached to the shaft 30.

From the foregoing description it will be obvious that I have provided an improved thermal compensating sprocket assembly and wheel therefor wherein provision is made for an extreme temperature differential between the outer rim of the wheel and the cooled hub portion thereof which may be cooled, for example, through an internally cooled supporting shaft.

The structure of the wheel 32 including the tooth 103 is disclosed and claimed in my parent application above identified.

The cooling mechanism is shown as cooling a high temperature shaft. Obviously, within certain aspects of my invention the same mechanism might conduct warm or hot water, or other cooling medium, to condition the temperature of a shaft by heating a normally cold one.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. A wheel, shaft, and bearing assembly the wheels of which are adapted to carry directly hot chain elements of a conveyer and the bearings of which are adapted to operate at relatively low temperatures and are protected against conducted heat, the assembly including a pair of spaced wheels having relatively thin peripheral portions adapted to receive and carry the hot chain elements, a shaft carrying said spaced

wheels having a bearing receiving portion adjacent each of its ends and a bore therein extending substantially centrally through each of said bearing receiving portions, bearing means receiving each of said bearing receiving portions of said shaft, insulation embedding said shaft between the bearing receiving portions thereof and embedding substantially completely said spaced wheels with the relatively thin peripheral portions only of the latter projecting through said embedding insulation for receiving and carrying the hot chain elements, said insulation resisting the transfer of heat to said wheels and shaft thereby protecting said bearings from heat, shaft cooling means cooperating with said insulation to protect said bearings from conducted heat including a pipe extending axially into each end of said bored shaft and within the bearing portions and spaced from the walls thereof for providing feed and return paths for cooling fluid, and means surrounding said pipes restricting the size and making the outer of said paths tortuous whereby a scouring turbulent flow of cooling fluid in contact with said shaft within said bearing areas occurs thereby removing heat conducted thereto through said spaced wheels and insulation.

2. A wheel, shaft, and bearing assembly the wheels of which are adapted to carry directly chain elements of a conveyer and the bearings of which are adapted to operate at relatively low temperatures and are protected against conducted heat, the assembly including a pair of spaced wheels having relatively thin peripheral portions adapted to receive and carry the chain elements, a shaft carrying said spaced wheels having a bearing receiving portion adjacent each of its ends and a bore therein extending substantially centrally through each of said bearing receiving portions, bearing means receiving each of said bearing receiving portions of said shaft, insulation embedding said shaft between the bearing receiving portions thereof and embedding substantially completely said spaced wheels, the relatively thin peripheral portions only of the latter projecting through said embedding insulation for receiving and carrying the chain elements, said insulation resisting the transfer of heat to said wheels and shaft thereby protecting said bearings from heat, shaft cooling means cooperating with said insulation to protect said bearings from conducted heat including a pipe extending axially into each end of said bored shaft and within the bearing portions and cooperating with the walls of the latter to provide feed and return paths for cooling fluid whereby cooling fluid flowing in said paths and in contact with the bore walls removes heat conducted thereto through said spaced wheels and embedding insulation.

3. A wheel, shaft, and bearing assembly the wheels and shaft of which are adapted to operate within a relatively hot area and the bearings of which are adapted to operate in a relatively cool area and are protected from heat conducted through said wheels and shaft from said hot area, said assembly including a pair of spaced wheels having relatively thin peripheral portions adapted to be exposed to heat in said hot area, a shaft carrying said spaced wheels including internally bored bearing receiving portions, one disposed outwardly of each of said wheels, bearing means carrying said bearing receiving portions of said shaft, insulation carried by said shaft between said bearing receiving portions

and substantially completely embedding said shaft and said spaced wheels except for the exposed thin peripheral portions thereof, said insulation resisting the transfer of heat to the body of said wheels and shaft thereby protecting said bearings from heat, and shaft cooling means cooperating with said insulation to protect said bearings from conducted heat including means cooperating with the walls of said bored bearing receiving portions to provide feed and return paths for cooling fluid whereby cooling fluid flowing in said paths and in contact with the bore walls removes heat conducted to the bearing receiving portions of said shaft, the insulation resisting the transfer of heat to the bodies of the wheels and shaft and the cooling means removing heat from the shaft conducted thereto from the exposed peripheries of the wheels and the heat which penetrates the shaft through the insulation.

4. A wheel, shaft, and bearing assembly the wheels and shaft of which are adapted to operate within a relatively hot area and the bearings of which are adapted to operate in a relatively cool area and are protected from heat conducted through said wheels and shaft from said hot area, said assembly including a pair of spaced wheels having relatively thin peripheral portions adapted to be exposed to heat in said hot area, a shaft carrying said spaced wheels including bearing receiving portions, one disposed outwardly of each of said wheels, bearing means

5
10
15
